FUMIGATING CAP

William C. Purdy, Tallulah, La.

Application July 19, 1935, Serial No. 32,300

2 Claims. (Cl. 220—87)

This invention relates to fumigating devices and particularly fumigating devices for substantially airtight containers, an object being to provide an improved structure which may be so mounted as not to be in the way at any time but to provide the desired fumigation at all times.

Another object of the invention is to provide a fumigating cap for containers for food or other ingredients wherein the vapor or gases from the chemicals may enter the container and be held against discharge therefrom.

An additional object, more specifically, is to provide in a container, a fumigating cap structure which may be readily mounted and which is provided with means whereby the contents may be readily charged from time to time.

In the accompanying drawing—

Figure 1 is an elevation of the upper part of a container showing an embodiment of the invention;

Fig. 2 is a bottom plan view of the cap and associated parts shown in Fig. 1;

Fig. 3 is an elevation of a foraminous plate forming part of the cap structure;

Fig. 4 is a view on an enlarged scale similar to the central part of Fig. 1 and illustrating a modified form of fastening structure.

Referring to the accompanying drawing by numerals, 1 indicates the body of the container, and 2 the upper end structure. The container 1 may be of any desired kind, as, for instance, the kind disclosed in my co-pending application, Serial No. 29,996, filed July 5, 1935. The end structure 2 is adapted to include a thickened end plate 3 which may be made up of a number of paper or fiber boards. The plate 3 is provided with an aperture into which the tubular portion 4 of a ring 5 is fitted. This tubular portion is threaded so as to receive the threaded wall 6 of a cap body 7.

The cap body 7, in addition to wall 6, is formed with a top 8, which merges into the wall 6 and the wall 6 in turn merges into an inturned flange 9, which flange is provided with notches or cut-away portions 10 as shown particularly in Fig. 2. Preferably the cap body 7 is formed on one integral piece and pressed into the shape just described, though it could be made in several pieces and soldered or secured together in any suitable manner. As illustrated in Fig. 1, there is provided a washer 11 which is clamped tightly in place beneath the ring 5 by any desired number of rivets 12. These rivets not only clamp the washer in place to provide a substantially airtight connection but hold the ring 5 with the threaded

portion 4 in proper position for receiving the cap body 7.

The cap body 7 is open at the bottom as shown in Fig. 1 and is filled with any kind of fumigating chemical which is held in place by a filling 13 of cotton. The cotton is saturated with the fumigating chemical and then placed in position, or, if desired, the cotton could be placed in position first and the fumigating chemical poured thereover until the cotton is saturated. After this has been done a foraminous plate 14 is positioned as shown in Fig. 1. This plate is a thin disk of metal with a number of openings therein and with a number of holding projections or protuberances 15. In the drawing three protuberances have been shown so positioned that they will register with the notches 10 and flange 9. The plate 14 is placed against the flange 9 and rotated until the protuberances snap into and pass through the notches 10 after which the plate 14 is rotated a short distance as indicated by the dotted lines 16 in Fig. 2. After the cap body has been assembled in this manner it is screwed tightly into the position shown in Fig. 1. The cap body may be removed from time to time and be filled as desired.

In shipping different kinds of food more or less in the dry state, it is desired under many circumstances to provide an insecticide or disinfectant which is in the nature of a vapor, and the present invention contemplates taking care of a situation of this kind. After the container 1 has been filled the cap body 7 is screwed into place and then the container is ready for shipment or storage. As shown in the drawing the cap structure is at the top of the container but it could be arranged at the bottom, or at both top and bottom, as none of the fumigating chemical comes directly in contact with any of the contents of the container but only the vapor from the cap body.

In forming the cap structure material of any sort may be used but it has been found desirable to use the cutout portion from the ring 2 as otherwise this material would be wasted. The ring 2 as clearly brought out in my copending application, is formed from metal and is substantially U-shaped in cross section at all points. The material left over after forming this ring is ample to form the entire cap structure. When the cap structure is positioned as shown in the drawing, the ring 5 and associated parts are inside the keg or container so that the ring and the tubular portion 4 cannot readily become loose but will at all times present the desired structure for the

cap member and a brace or reinforcement for the plate 3.

In Fig. 4 a slightly modified structure is shown wherein the cap body 7' is provided with a small tubular portion 6' fitting into a small tubular wall 4' extending from the flange 5'. The wall 4' is provided with a bayonet slot 17 for receiving the pin 18 carried by the wall 6'. Aside from the differences just pointed out, this structure is identical with that shown in Fig. 1 and functions in the same manner.

I claim:

1. A container, comprising a body having an end formed with a thickened plate provided with an aperture, a ring having a tubular threaded portion fitted into said aperture and an outturned flange overlapping part of said plate, a plurality of securing rivets extending through said flange and said plate for holding said ring in place, a gasket interposed between the ring and said plate for providing an airtight connection, a cap body having a solid end and threaded tubular member screwed into said threaded tubular portion, said

threaded tubular member being formed with an inturned flange, a fumigating carrying element arranged in said cap body, and a foraminous plate removably mounted on said inturned flange presenting a bottom closure for said cap body.

2. A fumigating cap structure for container including a tubular member, means for connecting the tubular member to part of the container, a cap body having a solid end, merging into a threaded tubular extension screwed into said tubular member, said tubular extension having an inturned flange notched at spaced intervals, means acting as a carrier for a fumigating substance, said means being arranged in said cap body, and a removable foraminous plate carried by said flange, said plate having radially extending projections normally resting on said inturned flange, said projections being slightly less in width than said notches and having the same spacing as said notches, whereby said plate may be easily applied and removed.

WILLIAM C. PURDY.
